Primary Examiner — Susan Bennett Hattan*Assistant Examiner* — Suzanne E Tisdell(74) *Attorney, Agent, or Firm* — Foley & Lardner LLP(57) **CLAIM**

We claim the ornamental design for a vehicle hood, as shown and described.

DESCRIPTION

FIG. 1 is a front perspective view of the claimed design; FIG. 2 is a front view of the claimed design; FIG. 3 is a rear view of the claimed design; FIG. 4 is a right side view of the claimed design; FIG. 5 is a left side view of the claimed design; FIG. 6 is a top view of the claimed design; and, FIG. 7 is a bottom view of the claimed design.

Evenly-spaced broken lines depict unclaimed portions of the vehicle hood. Broken lines in a dash-dot pattern depict boundaries between claimed and unclaimed portion of the vehicle hood, the boundaries themselves forming no part of the claim.
